WINDING MACHINE

Walter L. Beckwith, Jr., Warwick, R.I., assignor to Leesona Corporation, Warwick, R.I., a corporation of Massachusetts

Filed Apr. 29, 1965, Ser. No. 451,783
5 Claims. (Cl. 242—43)

The present invention relates to a winding machine and is directed more particularly to an improved traversing mechanism for controlling the path of movement of yarn or similar strandular material while winding the material at high speeds onto a take-up unit.

In the following specification and claims it is to be understood that the term "yarn" is used in the general sense to apply to all kinds of strand material either textile or otherwise, and the designation "package" is intended to mean the product of a winding machine whatever its form.

A variety of techniques have been proposed for traversing yarn at high speeds axially back and forth on a package core. By way of example, use of reciprocating or oscillating yarn engaging members carried on complementary, independently controlled, rotatable wheels, belts, chains or the like have been disclosed for traversing yarns. With these devices the yarn is traversed axially of a rotating package core in one direction by one of the independent members and is thereupon intercepted by the complementary, separately controlled member moving in the opposite direction. In consequence thereof, the yarn is shifted back to the opposite end of the package. This to and fro motion of the yarn results, of course, in its being traversed onto the supporting core to form a yarn package.

While prior art traversing mechanisms of the broad type under discussion may be successful under certain conditions it has been found in practice that difficulties arise with these known devices at the reversal points for the yarn, particularly when these mechanisms are operated at high speeds. That is to say, with such prior art mechanisms the yarn may not be deposited uniformly at the ends of the package, but rather may fall off the package end to cause a "stitch." Again, the yarn may be reversed at such speed as to cause the ends of the package to be softer or less dense than the mid-section of the package. Consequently, as the yarn builds up in layers the package is squeezed outwardly due to yarn compression at the inner section of the package thereby causing its side walls to collapse. Any of the foregoing conditions produce a package unsuitable for further processing and virtually impossible to unwind without causing the yarn to break.

Thus, the present invention provides a traverse mechanism for a winding machine wherein the yarn may be advanced at high speeds, in the order of 4,000 yards per minute and higher, while the yarn is traversed onto a core and reversed at the ends of the package in a positive manner thereby winding a cylindrical yarn package having highly acceptable configuration and characteristics for further use.

One object of the present invention is to provide a yarn traversing mechanism suitable for operation at high speeds.

2

A further object of the present invention is to provide a traverse mechanism capable of traversing yarns at high speeds without the use of reciprocating parts.

Yet, a further object of the present invention is to provide a traversing mechanism for traversing yarn axially of a package and for controlling the point of reversal of the yarn by positive means to thereby wind a package having parallel side walls devoid of stitches, ridges and other imperfections.

A further object of the present invention is to provide a traversing mechanism which is economical to manufacture, and yet highly reliable in use.

Other objects of the invention will in part be obvious and will in part appear hereinafter.

The invention accordingly comprises the apparatus possessing the construction, combination of elements and arrangement of parts which are exemplified in the following detailed disclosure and the scope of the application of which will be indicated in the claims.

For a fuller understanding of the nature and objects of the invention reference should be had to the following detailed description taken in connection with the accompanying drawing wherein:

FIG. 1 is a fragmentary front elevational view of a winding machine incorporating the improved yarn traversing mechanism of the present invention;

FIG. 2 is a top plan view of the apparatus of FIG. 1;

FIGS. 3, 4 and 5 are enlarged fragmentary front elevational views of the left-hand end of the yarn traversing mechanism, illustrating various steps as the yarn is reversed in its direction of movement; and

FIGS. 3a, 4a and 5a are top plan views of the structures of FIGS. 3, 4 and 5 respectively.

From the broad or general viewpoint the present invention contemplates the provision of an endless belt provided with a plurality of yarn traversing pins. The pins are embedded or otherwise supported along the side of the belt and extend laterally therefrom. The belt is carried on guide pulleys which serve to track and drive the belt. The pulleys direct the belt in a path so that it provides upper and lower generally horizontal belt runs or spans extending the length of a rotatable yarn package core. The upper and lower spans of the belt are disposed in horizontal planes parallel to each other. However, in the vertical plane these opposing spans are offset from alignment with one another. That is to say, the upper span of the belt is angled or offset in one direction and the opposing or lower span of the belt is offset in the opposite direction. Thus, in plan view, the upper and lower belt spans present a criss-cross or substantially X-shaped pattern, the midpoints of the two spans intersecting in the plane of the midpoint of the package core. Camming fingers are provided adjacent each end of the package core. These fingers are operable to receive the yarn from the traversing pins at each end of the package. Furthermore, the fingers act to damp vibrations in the yarn caused as the yarn is relieved from engagement with its traversing pin. With these vibrations controlled, the yarn will be suitably positioned for interception by a further traversing pin. Hence, an advancing strand of yarn being delivered to the package core from a fixed fanning point remote from the support is engaged, for example, by a yarn traversing pin in the upper span of the belt and

carried from left to right of the package core to traverse the yarn thereon. At the right-hand end of the package the yarn momentarily contacts one of the fingers. Thereupon, a further pin in the lower span of the belt engages the yarn to traverse it in the reverse direction to the left-hand end of the package and engage it against a further finger. By virtue of the fact that the belts are angled with respect to each other causing the particular pin which traverses the yarn at any given interval to move in a horizontal path from a position relatively close to the periphery of the package progressively outward to a position further removed from said package, and in light of the fact that the yarn is being delivered from a fixed fanning point and traversed onto a package core in a straight-line path, the yarn tends to slide outwardly to the outer end of its yarn delivery pin as the yarn is traversed axially of the package core. This facilitates removal of the yarn from each yarn traversing pin by the fingers at the appropriate instant. Furthermore, the normal straight-line path of the yarn is not interfered with to any significant degree during such action.

Referring now, in detail, to the drawings, wherein a preferred embodiment of the present invention is illustrated, and with particular reference at the outset to FIGS. 1 and 2, a winding spindle 10 is shown as supported for rotation in a bearing 11 positioned in the winding head 12 of a winding machine 13 of the type, for example, disclosed in U.S. Patent 2,740,590 issued Apr. 3, 1956, to J. V. Keith. As described in said patent, winding head 12 is movably mounted thereby permitting the head and spindle 10 to rock toward and away from a roller bail 14. Said bail is rotatably mounted in bearings 15 attached to a stiff support plate 16. A fixed yarn guide 17 also constitutes a part of the machine and is arranged in alignment with the axial midpoint of a package core C carried on spindle 10.

Spindle 10 may be arranged in any convenient manner to mount the package core C thereon whereby the core will rotate with the spindle 10 to permit winding of a yarn package P thereon and such that the package and core can be removed at the completion of the winding cycle. The machine 13 provides a mount for an angular member 18 extending from the side thereof. In turn, member 18 has the elongated plate 16 securely affixed thereto as by bolts 19. Plate 16 extends from the side of machine 13 generally rearwardly of and parallel to shaft 10 and projects slightly past the outer end of said shaft. As illustrated in FIGS. 1 and 2, a plurality of pulleys (here shown to be three in number) referenced as 20, 21 and 22 are arranged in a triangular pattern at the inner end of plate 16. Pulley 20 serves as the driver and is secured to a power shaft 24 which, in turn, is connected with a suitable source of power (not shown) for rotating the shaft. Pulleys 21 and 22 are rotatably mounted on studs 26 and 27, respectively. Each of the nut studs 26, 27 is threaded at its inner end to receive a nut 28, 29, respectively thereby fixing these studs in position on plate 16.

The opposite or outer end of plate 16 is provided with a further series of pulleys 30, 31 and 32, each rotatably supported on a respective stud 35, 36 and 37. The inner ends of each of the studs 35, 36 and 37 are threaded to receive an associated nut 38, 39 and 40 for securing the studs in position on plate 16. As best shown in FIG. 2, the several studs 26, 27, 35, 36 and 37, in addition to shaft 24 are all canted away from a plane normal to the surface of plate 16 in a manner to direct an endless belt 40 which passes around the several pulleys 20, 21, 22, 30, 31 and 32 in a skewed path. Thus, the belt moves in a path deviating from a straight line parallel to shaft 10. It will be observed in FIG. 2 that belt 40 is disposed in the zone between shaft 10 and plate 16. As the belt is driven in a clockwise direction, i.e., in the directions of the arrows, its upper span is delivered off pulley 32 from a somewhat forward position, i.e., relatively closer

to shaft 10 than to plate 16, and follows a slightly rearward path angling toward plate 16 as it moves from a position proximate one end of core C to the other. The belt is then lead about pulleys 22 and 20 in a fashion to be once again shifted forwardly to essentially the forward position on pulley 20 corresponding to that from which it was delivered off pulley 32. The lower span of belt 40 is then moved to the left (FIG. 2) off pulley 20 as the belt continues its clockwise movement and passes through the plane of the axial confines of core C. The belt 40 is thereupon received initially on pulley 31 whereupon it is moved over the periphery of pulley 30 and pulley 32 thereby completing one full revolution or pass. As the belt 40 moves from right to left, i.e., from pulley 20 to pulley 31 it once again follows a somewhat rearwardly course as illustrated in FIG. 2. The angular paths of the upper and lower spans of belt 40 are offset from the surface of plate 16 approximately 3° and the axes of the upper and lower belt spans across in the plane of the midpoint of package P. It should be noted again, however, that in the horizontal plane the upper and lower reaches or spans of belt 40 are parallel to each other. Furthermore, belt 40 may be a timing belt, if desired, in which event the pulleys would be provided with grooves to mate with the teeth of the belt, all in the manner well known in the art.

Belt 40 is provided with a plurality of yarn traversing pegs or pins 42 of uniform length which are embedded in the side or edge of the belt. These pins are spaced apart along the belt, the spacing being a distance generally equal to twice the length of the package to be wound. As best seen in FIG. 2 these pins are bent slightly rearwardly so that the outer end of each pin 42 is in a trailing position to the remainder of the pin as the belt 40 moves clockwise in FIGS. 1 and 2. As will be more fully explained hereafter, these pins cooperate to traverse the yarn onto core C.

A horizontal bracket 44 is fastened to plate 16 and, as seen in FIGS. 1 and 2, resides in radial alignment with package core C. A pair of fingers 45, 46 having inclined sides serving as cam edges 47, 48 respectively, are affixed to the top of bracket 44 by screws 49, 50. The fingers 46, 48 are adjustable longitudinally of bracket 44 by virtue of elongated slots in the fingers through which the screws 49, 50 pass. As seen in FIGS. 1 and 2, fingers 45, 46 are located at opposite ends of core C and their edges 47, 48 cooperate with pins 42 to displace the yarn from one pin and transfer it to a further pin, all to effectuate reversal of the traversing direction of the yarn. As is best seen in FIG. 1 a pair of auxiliary tracking pulleys 52, 54 are affixed rotatably on studs 56, 58 respectively, which depend from an associated one of a pair of spaced blocks 60, 62 welded to plate 16. Pulleys 52, 54 aid in tracking belt 40 during its course of movement.

In operation, the apparatus is threaded up by drawing a strand of yarn Y from a suitable supply source, through yarn guide 17, and attaching it to core C in a conventional manner. Fingers 45, 46 are adjusted to positions at opposite sides of core C such that they will engage the yarn at the respective package ends to remove the yarn from any one of the yarn traversing pins. In operation the yarn will contact the fingers while it is still engaged by any one of the pins. Yet, because of the inclination of the cam edges 47, 48 the yarn will simply slide off the pin and up the inclined edge of the related finger to allow the pin to pass. It is important to note, however, that the yarn will not slide along the edge so as to be out of alignment with the oncoming pin which will convey the yarn in the opposite direction. This is due to the fact that the oncoming pin is always approaching the finger and, hence, the released yarn from a position projecting substantially further forwardly than the point where the yarn is deposited on the respective finger, as illustrated in FIG. 4a. Thus, the yarn strand is always positioned for interception by another pin, promptly upon its release by a

given pin. With fingers 45, 46 adjusted spindle 10 is rotated and belt 40 is driven from its power source through shaft 24. In consequence thereof one of the pins 42 will engage the yarn and move it across the core in one direction whereupon the yarn will slide off said pin against one of the cams 47, 48 to be engaged by and traversed in the opposite direction by a further pin.

FIGS. 3-5a are illustrative of the action of the elements of the invention in effecting reversal of the yarn at the lefthand end of the package (viewing FIGS. 1 and 2). It will be appreciated that reversal of the yarn would be effected similarly at the opposite end of the package. In FIGS. 3 and 3a the yarn Y is seen to be engaged by one of the pins 42. It will be observed further from FIG. 3a that the yarn is riding on the bent or trailing portion of the pin. In accordance therewith, the length of the pins is carefully controlled consistent with the angularity of the belt 40 and in keeping with the slope of the cams 47, 48 whereby as the yarn moves across the core C and package P it gradually migrates laterally of the pin toward the outer end thereof so that the yarn is adjacent the outer end of the pin just prior to engagement by one of the cam edges 47, 48, having moved to that outer end position from an initial or beginning position somewhat closer to belt 40 (see FIG. 5a).

As the yarn Y is moved against edge 47 the traversal movement of the yarn in the direction of travel of the pin carrying it is, of course, stopped thereby while pin 42 continues its motion toward the left and, as seen in FIG. 4 the pin slides past the yarn, the yarn riding slightly up the sloping edge of the cam to permit passage of the pin. Such communication of the yarn with edge 47, while very brief in time, damps any vibration induced in the yarn during its removal from pin 42, thus, insuring the yarn will be aligned for engagement by the oncoming pin. The yarn, which is momentarily checked against edge 47, immediately begins to move away from said edge to slide toward said package midpoint, since the yarn is under tension and is diverted from its normal yarn path in alignment with the axial midpoint of package P.

FIGS. 4 and 4a illustrate the yarn shortly after it has been disengaged from one pin and just prior to its being picked up by a further pin. During this period when the yarn is very briefly relieved of control by any of the pins 42 it migrates from either end of the package inwardly at a speed proportionate to the angle of deflection of yarn from its normal path in alignment with the axial midpoint of the package. Therefore, if a more rapid return of the yarn is desired the fanning point, i.e., yarn guide 17, would be moved closer to package P. Thus, package ridges, caused by variations in the traversal rate of the yarn when under free traversal, as opposed to the condition when the yarn is positively traversed by pins 42 can be reduced to any period or rate without recourse to tension adjustments in the yarn. However, it should be noted that whatever rate of return of the yarn is selected, the starting of yarn return from either end of the package toward the center occurs immediately when the traversing pin 42 which delivered the yarn across the package has dropped the yarn against a respective one of the edges 47, 48, there being virtually no lag of the yarn at the package ends. As the yarn commences its free movement toward the package midpoint, a further yarn traversing pin 42 is rapidly brought into engagement with the yarn to move the yarn positively in this opposite direction, as shown in FIGS. 5 and 5a. Moreover, it will be observed in these last two mentioned views that the yarn is seated against the inner portion of the pin 42, i.e., that section of the pin normal to the edge of belt 40, the yarn once again migrating toward the outer end of the pin as it is traversed to the opposite end of the package. Tendency of the yarn to develop minute ridges on the package, as may occur especially during periods when the yarn is under traversal free from contact with any of the pins 42, is 75

compensated for by roller bail 14 which acts to smooth the package surface.

From the foregoing it will be evident that the instant invention provides means for traversing yarn axially of a core to wind a package, such traverse being capable of operation of high speeds, i.e., in the order of 4000 yards per minute and higher, while winding a package having straight, uniform side walls and providing uniformity in the circumference of the package. Furthermore, it will be observed, particularly from FIGS. 3a, 4a, and 5a that the unique arrangement of the present invention causes the yarn being carried across the package by an active traversing pin to be deposited inwardly on the cam edge of the particular finger 45, 46 against which the yarn is moved. At the same time the next pin which will convey the yarn in the opposite direction approaches the yarn from a position quite forwardly of the finger (see FIG. 4a). Thus, even though some forward movement of the yarn along the cam edges 47, 48 may occur when the active delivery pin passes, as previously described, still the yarn is always aligned in the path of the oncoming pin since the forward displacement of the yarn on the finger is never of such magnitude as to carry it outside the confines of the path of the on-coming pin. Therefore, the yarn is always in readiness for instant traversal in the opposite direction. This precludes the necessity of any lag at either end of the package while the yarn is realigned for reception by the on-coming pin.

Since certain changes may be made in the apparatus without departing from the scope of the invention herein involved, it is intended that all matter contained in the above description or shown in the accompanying drawing shall be interpreted as illustrative only and not in a limiting sense.

What is claimed is:

1. Apparatus for winding yarn comprising:
  - (A) means for rotatably supporting a core onto which yarn delivered from a supply is wound into a package, said package having first and second sides;
  - (B) a single and continuous movable means having a flat portion and an end portion;
  - (C) a plurality of traversing elements affixed at their respective inner ends into said end portion of said movable means and having their respective outer ends projecting therefrom;
  - (D) cam means positioned adjacent said first and second sides of said package, and
  - (E) support means for positioning said movable means to provide first and second oppositely extending and criss-crossing spans, said first span being disposed to move in a path from a first position corresponding to a first side of said package where an active one of said traversing elements in said first span engages said yarn and traverses it across said package to a second position corresponding to a second side of said package where said active traversing element of said first span disengages from said yarn; said second span being disposed to move in a path from a first position corresponding to said second side of said package where an active one of said traversing elements in said second span engages the yarn and traverses it across said package to a second position corresponding to said first side of said package where said active traversing element of said second span disengages from the yarn; said criss-crossing occurring substantially at the mid-point of said package, said traversing elements, cam means and the angle of said movable means being constructed and arranged in order that the traversing element engaging said yarn and the traversing element disengaging said yarn converge substantially simultaneously, moving in opposite directions, at a point on said cam means, whereby said traversing element disengaging said yarn strand is at substantially the same height as said cam surface at point

of contact, and said traversing element engaging said yarn is of substantially greater height than said cam surface at point of contact.

2. Apparatus as set forth in claim 1 including guide means located between a supply source and said package, said guide means acting to direct the yarn advancing to said package in the path of movement of said traversing elements.

3. Apparatus as set forth in claim 1 wherein said first and second spans move in parallel horizontal paths.

4. Apparatus as set forth in claim 1 wherein said traversing elements are elongated members, each having a yarn guiding surface, the yarn being slidable on said surface toward the outer end of the active traversing element on said first span as said first span moves toward its second position, and the yarn being slidable on said surface toward the outer end of the active traversing element on said second span as said second span moves toward its second position.

5. Apparatus as set forth in claim 1 wherein each said traversing element includes an inclined portion of said outer end thereof for facilitating movement of the yarn off each said element.
